UNITED STATES PATENT OFFICE.

WILLIAM F. SCHMIDT, OF WYANDOTTE, MICHIGAN, ASSIGNOR TO ALL METAL PRODUCTS COMPANY, OF WYANDOTTE, MICHIGAN, A CORPORATION OF DELAWARE.

TOY PISTOL.

Application filed February 1, 1924. Serial No. 689,936.

To all whom it may concern:

Be it known that I, WILLIAM F. SCHMIDT, citizen of the United States, residing at Wyandotte, county of Wayne, State of Michigan, have invented a certain new and useful Improvement in Toy Pistols, and declare the following to be a full, clear, and exact description of the same, such as will enable others skilled in the art to which it pertains to make and use the same, reference being had to the accompanying drawings, which form a part of this specification.

My invention relates to toy pistols and the object of my improvements is to secure 15 cheapness, strength and efficiency in the construction, and as a special reference to that kind of pistol which is operated by the manipulation of the trigger piece. I secured this object in the construction shown in the 20 accompanying drawing in which Fig. 1 is a side elevation of a pistol embodying my invention.

Fig. 2 is a longitudinal section substantially in a vertical plane through the axis 25 of the barrel.

Fig. 3 is a detailed section on the line III, III, Fig. 2.

Fig. 4 is a perspective view of the piston retracting piece.

30 Fig. 5 is a section on the line V, V, Fig. 4.

Fig. 6 is a section substantially on the line VI, VI, Fig. 4.

a is the stock which also supplies the handle. This stock is made of two stampings 35 joined together at their adjacent edges by rivets in a known way. *b* is the barrel clamped between the two halves of the stock *a*. *c* is the piston reciprocated in the barrel *b* and projected outward by the spring *c*.

40 *c*² is the retracting rod secured axially to the piston *c* and extending backward through the center of the barrel *b* and into the hollow of the stock *a*, back of the barrel. The rear end of the rod *c*² is provided 45 with a slot or loop *c*³ opening vertically. *d* is the trigger piece loosely pivoted around the rivet *d*² at its upper end and engaging in a slot in the forward edge of the handle. *d*³ is a lug projecting forward from the

50 trigger *d* and engaging at its upper end back of the spring *c*⁴, so that said spring shall hold the trigger piece normally in the position shown in Figs. 1 and 2. The trigger *d* is made up of sheet metal bent over 55 upon itself as shown at *d*⁴, Fig. 3.

*d*³ is a lug turned up from an inner edge of the inner fold of the sheet metal of which the trigger *d* is composed.

e is a lever arm pivoted with some lost motion around the rivet *e*², which engages the stock *a* at its ends. The upper end of the arm *e* is turned over at right angles to form a lug or stop *e*³. The upper end of the arm *e* passes through the slot *c*³ and the lug or stop *e*³ is of sufficient length to prevent the upper end of said arm passing vertically through said slot. The right hand edge of the arm *e* engages the right hand end wall of the slot *c*³. *e*⁵ is a lug extending at right angles from the left hand edge 60 of the arm *e* at its lower edge and at its upper edge curving to the right and forward to form a part of the left hand edge of the arm *e*. The edge of the arm *e* between the lugs *e*³ and *e*⁵ is bent outward at *e*⁴, as shown 65 most distinctly in Figs. 4, 5, and 6. The lug *d*⁵ extends outward from the inner portion of the trigger *d* within the stock *a* and engages under the lower edge of the lug *e*⁵.

The operation of the above described device is as follows: The parts being in the position shown in Fig. 2, the handle is 70 grasped and the trigger *d* forced inward to the position shown in broken lines. This raises the lug *d*⁵ which forces the lug *e*⁵ upward, rocking the arm *e* about the rivet *e*² to the position shown in broken lines in Fig. 2. The right hand edge of the arm *e* engaging the end wall of the slot *c*³ in the 75 retracting rod *c*, forces said rod backward to the position shown in dotted lines, drawing the piston *c* inward against the action of the spring *c*⁴. The turning of the arm *e* around the rivet *e*² carries the lug *e*⁵ backward until its end passes beyond, and out of engagement with the lug *d*⁵, when the piston *c* is driven forward by the spring carrying the arm *e* back to its first position. 80

The trigger piece *d* is now released and the spring *c*⁴ forces the trigger piece *d* back to its original position, the lug *d*⁵ engaging against the end surface of the arm *e* where said arm is bent outward at *e*⁴. The material of the trigger *d* permits the lug *d*⁵ to be forced inward by its engagement with the slanting surface of the arm *e* at *e*⁴, and the arm *e* may move somewhat outward because of its lost motion. Thus, the lug *d*⁵ passes under the arm *e* and when it has 85 passed the lower edge of said arm the re- 90

110

silence of the material of the trigger *d* and the tendencies of the parts to resume their normal position, snaps said lug again into engagement as shown in broken lines in Fig. 5 2, and the operation may again be repeated.

What I claim is:

1. In an apparatus of the kind described, a trigger piece and a retracting piece, said trigger piece engaging said retracting piece 10 to actuate the same and to cause it to pass out of engagement with said trigger piece, said pieces being adapted to have a relative lateral motion to permit the return of said trigger piece to its engaging position.
- 15 2. In an apparatus of the kind described, a retracting piece having a part adapted to be engaged, and a lateral slanting part adjacent and opposite said engaging part, a trigger piece adapted to engage said engaging part to actuate the actuating part and to engage said slanting part to pass into engaging position.
- 20 3. In an apparatus of the kind described, a retracting piece having a part adapted to

be engaged, and a lateral slanting part 25 adjacent and opposite said engaging part, a trigger piece adapted to engage said engaging part to actuate the actuating part and to engage said slanting part to pass into engaging position, said retracting part having a lug with a straight edge and being bent outward, opposite, and adjacent to said straight edge to present said slanting surface.

30 4. In an apparatus of the kind described, a trigger piece and a retracting piece, said trigger piece engaging said retracting piece to actuate the same and to cause it to pass out of engagement with said trigger piece, said pieces being adapted to have a relative lateral motion to permit the return of said trigger piece to its engaging position, one of said pieces being made of thin metal bent upon itself to secure lateral resiliency.

45 In testimony whereof, I sign this specification.

WILLIAM F. SCHMIDT.
